COMBINED PHONOGRAPH AND LOUD SPEAKER CABINET

Samuel E. Adler, Chicago, Ill., assignor to Admiral Corporation, Chicago, Ill., a corporation of Delaware

Application January 13, 1955, Serial No. 33,962

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combined Phonograph and Loud Speaker Cabinet, of which the following is a specification, reference being had to the accompanying drawings, forming a part hereof.

Fig. 1 is a perspective view of a combined phonograph and loud speaker cabinet, showing my new design;

Fig. 2 is a top plan view thereof with the compartment cover being shown in an open position; and,

Fig. 3 is a fragmentary side elevational view thereof, a front portion being broken away for purposes of illustration.

The dominant features of my design reside in those portions shown in full lines.

I claim:

The ornamental design for a combined phonograph and loud speaker cabinet, as shown and described.
